(57) **CLAIM**

The ornamental design for a CATV housing with heat sink fins, as shown.

DESCRIPTION

FIG. 1 is a top perspective view of the present invention; FIG. 2 is a right side view thereof;

FIG. 3 is a left side view thereof;

FIG. 4 is a front view thereof;

FIG. 5 is a back view thereof;

FIG. 6 is a top view thereof; and,

FIG. 7 is a bottom view thereof.
